LAUNDRY PRESS

Alonzo Linton Bausman, Springfield, Mass.

Application November 13, 1931
Serial No. 574,788

5 Claims. (Cl. 60—52)

This invention relates to laundry presses of the type having a fixed lower buck and an upper head movable toward the buck by power-operated mechanism. One object of the invention is 5 to improve the power mechanism for operating a press of this character. A further object is to provide a press of this character with simple control means necessitating the use of both hands of the operator to close the press. A further 10 object of the invention is to utilize the power operating mechanism to check the opening movement of the head. A further object of the invention is to provide a counter-balancing spring so designed as to exert a breaking action on the 15 press-operating toggle. Additional objects will appear from the following description and claims.

Referring to the drawings:

Fig. 1 is a side elevation partly in section of a press embodying the invention; 20
Figs. 2 and 3 are diagrammatic views illustrating the method of operation of the press;
Fig. 4 is a partial front elevation looking from the right in Fig. 1;
Fig. 5 is a section through the press-operating cylinder and associated parts, taken on line 5—5 of Fig. 1;

Fig. 6 is a section on line 6—6 of Fig. 1;
Fig. 7 is a section on line 7—7 of Fig. 1;
Fig. 8 is a section on line 8—8 of Fig. 1;
30 Fig. 9 is a section on line 9—9 of Fig. 1; and
Fig. 10 is a section on line 10—10 of Fig. 9.

The press is mounted on a frame 10 which, in the case shown, is formed of structural iron rather than from a casting to produce strength with the 35 least weight and expense. The frame supports a stationary buck 11 which may be of any usual form and is, therefore, not described in detail. One or more arms 12 are pivoted at 13 to the frame and carry an upper head 14 in any conventional manner. To the arms 12 spaced links 15 are pivoted as at 16. The lower end of each of 40 these links is pivoted at 17 to a pair of links 18 swinging at 19 upon the frame and embracing the link 15 between them. This construction permits the use of ordinary bar steel and does not require special castings.

The links 15 and 18 form a toggle which, when straightened, swings the arms 12 to press the head against the buck. To straighten this toggle 50 a link 20 passes between each pair of links 18 and is secured to them by a pivot 21. At its opposite end a pivot 22 joins each link 20 between a pair of links 23 pivoted at 24 to the frame. A cylinder casting 25 is supported in the frame as by channel irons 26 and is formed with a top 27. A

piston 28 runs in a cylindrical bore 29 formed with a casting 25, and carries a rod 30 extending upwardly through the top 27 and secured to a cross head 31. This crosshead runs upon guide rods 32 fastened to the top 27 and extending loosely through the crosshead. Springs 33 encircle the guide rods above the crosshead and are held in position by nuts 34. These springs serve both as shock absorbers slowing down the action of the piston as it nears the end of its press closing stroke and as a means to exert a breaking action on the toggle 20, 23 when the piston starts its descent. At each end of the crosshead is a pin 35, swinging on which is a link 36 pivoted at 37 between one pair of links 23, thus in effect 60 connecting the piston rod to the toggle 20, 23. 65

In order to open the press, counterbalancing springs 38 are employed, serving to overcome the weight of the head 14 and to run a part of the hydraulic driving mechanism to be described 70 later. The springs are also arranged to break the toggle 15, 18 at the start of the press opening movement, as no mechanism has been provided for reversing the operation of the hydraulic driving device. For this purpose the 80 springs are stretched between arms 39 freely mounted on the pivots 16 and 19 and carrying lugs 40 bearing against the outer sides of the links 15 and 18. It will be seen that in addition to the usual function of pulling downwardly upon 85 the rear ends of the arms 12 the springs exert a turning force on the toggle links tending to break the toggle and thus permit the press to open.

The piston 28 is, in accordance with the preferred form of the invention, driven hydraulically. For this purpose a motor 45, which runs constantly during the operation of the press, is directly connected to a pump 46 of the centrifugal type. The detail construction of this pump is not of importance and has, therefore, 90 not been illustrated. The centrifugal type is chosen because it permits of the continued rotation of the driving motor even though the outlet of the pump is shut off. Any pump having this characteristic can be used. The inlet of the pump is indicated in the drawings at 47 and the outlet at 48. The outlet 48 from the pump runs into a distributing chamber 49 formed within the cylinder casting 25 and separated from the cylinder 29 by a passage 50, shown in Fig. 1 and diagrammatically in Fig. 2. This distributing chamber is located near the bottom of the cylinder casting and has above it a reservoir 51. This reservoir is separated from the distributing chamber by a partition 52 and has an open con- 100

105

110

nection 53 with the top of the cylinder 29. Between the distributing chamber and the reservoir are two valves 54, 55 acting in parallel, as shown in Fig. 2. The valves are composed respectively of disks 56, 57, each disk having spaced holes which in one position of rotation of the disk are adapted to register with holes 59 in the partition 52. The valves are rotated by rods 60 and 61 respectively, each rod having secured to its upper end an arm 62 joined by a link 63 with one arm of a bell crank 64 mounted on the frame. Links 65 connect the two bell cranks to spaced handles 66 and 67 mounted on the front of the frame, so that each valve is controlled by a separate handle. A spring 68 tends to draw the rear end of each handle downwardly as viewed in Fig. 1, and springs 69 tend to keep the valves 54, 55 against their seats. Also mounted upon the rods 60, 61 are valves 70 and 71, the first cooperating with the pump inlet 47, and the second with the pump outlet 48. Both of the valves 70, 71 are loose fitting for a purpose to be described.

The operation of the hydraulic actuating means will now be described. It will be assumed that the cylinder 29, the distributing chamber 49, and the reservoir 51 are filled with oil or other liquid suitable for the purpose. The pump 46, as previously stated, is rotating constantly. While the press is open, the two valves 54 and 55 are open between the distributing chamber and the reservoir, so that, as best shown in Fig. 3 (which shows the piston starting down), a complete by-pass is established around the cylinder 29. No action upon the piston 28 will, therefore, occur. The loosely fitting valves 70, 71 are closed during this time so that a partial load is placed upon the centrifugal pump. This serves both to cut down the speed with which the circulation of oil takes place, preventing the momentum of oil from exerting an undesired action upon the piston, and to prevent the pump from being suddenly left unloaded.

If it is desired to close the head of the press upon the buck, both of the handles 66 are lowered, thereby shutting the valves 54, 55, as in Fig. 2, and opening the valves 70, 71. This prevents flow of oil from the distributing chamber to the reservoir and forces it underneath the piston 28. As the piston rises, the head is lowered upon the buck by the toggle connections described above. As the head comes into place against the buck, the piston necessarily stops. This, however, does not affect the action of the pump which keeps in operation and maintains a steady pressure of the head against the buck.

It will be observed that it is necessary to operate both handles 66 since if only one of them is moved a by-pass is still established between the distributing chamber and the reservoir. This requires the operator to have both hands out of the way of the press head at the time when the latter is closed.

In order to relieve the operator of the necessity of keeping his hands upon the handle 66, 67 during the period when the press is to remain closed, a bracket 75 is fixed to the crosshead 31 and carries a bow spring 76, each end of which presses against the rear end of one of the handles 66, 67, as shown in Figs. 1 and 6. It is necessary for the operator to keep the handles depressed until the press is fully closed, but as soon as this occurs the press will remain closed without further attention on his part, as long as may be desired. When the press is to be opened, one of the handles 66 or 67 (it being immaterial which

one) is elevated. This opens one of the valves 54 or 55 and closes the corresponding valve 70 or 71. This opens a connection between the distributing chamber 45 and the reservoir 51, giving a chance for the liquid underneath the piston 28 to flow directly into the reservoir in which the liquid is under no substantial pressure. It also chokes off either the inlet or outlet of the centrifugal pump, thus preventing the sudden circulation of the liquid at a high speed when the connection to the reservoir is open. As soon as the piston descends, the spring 76 is moved away from the valve handles 66 and 67 so that the press will remain open without further attention.

The counter-balance spring 38 which opens the press imparts considerable momentum to the mechanism during the opening operation, and it is desirable to slow the parts down before they reach their final position of rest. In the present case, this is accomplished by a short reversal of the valve mechanism at a time just prior to the full opening of the press. To do this, the crosshead 31 is provided with spaced abutments 77, each adapted to contact with an arm 78 pivoted at 79 to a bracket formed upon the cylinder top 27. Also pivoted at 79 are bell cranks 80, one arm of each of which carries a set screw 81, making contact with one of the arms 78, and the other arm of which is connected by a link 82 to the same arm of the bell crank 64 to which the link 63 is fastened. As the crosshead descends, the abutment 77 strikes the arm 78, rocking the bell cranks 80 and 64 and turning the valves as if the handles 66, 67 had been depressed to cause closure of the press mechanism. In the present case, however, this action is only transitory, the abutment quickly passing by the ends of the arms 78 and allowing these to return to their initial position. The action lasts for a long enough time to build up a slight pressure under the piston 28 and to slow it down in its travel. As soon as the abutments pass the arms, the pressure under the piston is released and it is permitted to sink into its final position.

As stated above, the buck and head may be of any type desired. In the case shown, the heater 85 has been indicated underneath the buck 11. This heater may be of any of the usual types adapted to heat air by circulation of steam 125 through a coil. The buck is made hollow so that air may rise through the heater either by gravity or by a fan which may, if desired, be inserted in the system.

According to a further refinement illustrated in Fig. 1, a by-pass 90 joins portions of the cylinder 29 straddling the piston 28 when the latter is in its raised position. A valve 91 controls the passage of liquid through this by-pass, so that when the press is fully closed a predetermined quantity may be shunted around the piston. This controls by a simple adjustment the pressure with which the two press heads are forced together.

I claim:

1. A laundry press comprising opposed press members, power transmitting mechanism connected to one of the press members for transmitting a press closing force to it, cylinder and piston mechanism connected to said transmitting mechanism, a reservoir, a distributing chamber connected to the cylinder, a constantly driven centrifugal pump having its inlet connected to the reservoir and its outlet connected to the distributing chamber, valve means for connect-

- ing the distributing chamber to the reservoir, and means for choking the free flow of fluid through the pump when the valve means between the distributing chamber and the reservoir is open.
- 6 2. A laundry press comprising opposed press members, power transmitting mechanism connected to one of the press members for transmitting a press closing force to it, cylinder and piston mechanism connected to said transmitting mechanism, a reservoir, a distributing chamber connected to the cylinder, a constantly driven centrifugal pump having its inlet connected to the reservoir and its outlet connected to the distributing chamber, valve means for connecting the distributing chamber to the reservoir, manual control means for closing the valve means to cause closing of the press, means for opening the press, and mechanism automatically operable during the opening of the press to cause a transitory closing of the valve means to check the opening of the press. 80
- 10 15 19. 2. A laundry press comprising opposed press members, power transmitting mechanism connected to one of the press members for transmitting a press closing force to it, cylinder and piston mechanism connected to said transmitting mechanism, a reservoir, a distributing chamber connected to the cylinder, a constantly driven centrifugal pump having its inlet connected to the reservoir and its outlet connected to the distributing chamber, a pair of valves for connecting the distributing chamber to the reservoir, separate spaced manual controls for said valves, and a second pair of valves connected to the first pair for actuation therewith for choking the flow of fluid through the pump inlet and outlet when the first named valves are open. 85
- 20 25 30 35 40 45 50 55 60 65 70 75 80 85 90 95 100 105 110 115 120 125 130 135 140 145 150
3. A laundry press comprising opposed press members, power transmitting mechanism connected to one of the press members for transmitting a press closing force to it, constantly running press closing power means connected to said power transmitting mechanism, means for rendering said constantly running power means ineffective in its operation in order to open the press, and mechanism automatically actuatable during the opening of the press for causing a transitory effectiveness of operation of the power means to check the opening of the press. 100
4. A laundry press comprising opposed press members, power transmitting mechanism connected to one of the press members for transmitting a press closing force to it, cylinder and piston mechanism connected to the power transmitting mechanism, a fluid pump adapted to force a substantially incompressible fluid into the cylinder to cause press closing movement of said mechanism and by its continued operation to exert a continuing pressure between the press members, and a regulable by-pass adapted to shunt fluid by the piston when the latter is in press closing position only whereby adjustment may be made of the pressure with which the press members are forced together. 105
